Patented Mar. 21, 1922.

INVENTOR,

Lent Luzern Custer,

BY Thomas S. Smith.

His ATTORNEY.

UNITED STATES PATENT OFFICE.

LEVITT LUZERN CUSTER, OF DAYTON, OHIO.

DESIGN FOR A TOY AUTOMOBILE.

0,643.

Specification for Design. Patented Mar. 21, 1922.

Application filed December 7, 1920. Serial No. 429,003. Term of patent 3½ years.

To all whom it may concern:

Be it known that I, LEVITT LUZERN CUSTER, a citizen of the United States, residing at Dayton, in the county of Montgomery and State of Ohio, have invented a new, original, and ornamental Design for a Toy Automobile, of which the following is a specification, reference being had to the accompanying drawing, forming part hereof.

The figure is a perspective view of a toy automobile, showing my new design.

I claim:

The ornamental design for a toy automobile, as shown.

LEVITT LUZERN CUSTER.

Witness:

HOWARD S. SMITH.
